UNITED STATES PATENT OFFICE.

PREM NARAYAN, OF BIJNOR, INDIA.

FOUNTAIN PEN.

Application filed April 7, 1923. Serial No. 630,539.

To all whom it may concern:

Be it known that I, PREM NARAYAN, a subject of the King of Great Britain and Ireland, residing at Bijnor, United Provinces, India, have invented new and useful Fountain Pens, of which the following is a specification.

My invention relates to fountain pens of the kind in which the nib is projected into its operative or writing position without requiring the removal of a cap or like detachable cover.

One object of my invention is to improve the means whereby the nib, when not required for use, is concealed and protected within the body or casing of the pen.

Another object of my invention is to provide improved means whereby the nib may be readily moved into or out of the body or casing of the pen, said movement being effected with ease and rapidity by a one-hand manipulation.

Another object of my invention is to provide means for preventing the flow of ink through the nib when the latter is in the retracted or inoperative position.

A further object of my invention is the provision of means whereby the accidental or unintentional manipulation of the device for moving the nib into its operative position is prevented.

A still further object of my invention is to provide in a fountain-pen of the kind above referred to, and of the type known as self-filling, means whereby the self-filling lever is locked against manipulation when the nib is in the retracted or inoperative position.

Referring to the drawings which form part of this specification, Fig. 1 is an elevation of the improved pen, Fig. 2 is a part-sectional view at 2—2 of Fig. 1, Fig. 3 is a section to an enlarged scale at 3—3 of Fig. 2, Fig. 4 is a view of the pen-barrel detached, Fig. 5 illustrates to an enlarged scale the fitting comprising the pocket-clip and the self-filling lever, Figs. 6 and 6^a are respectively an elevation and plan view of a closure-member hereinafter referred to, and Fig. 7 is an end view of the pen with the nib in the retracted position.

The nib 1, feed-bar 2, and an attachment 3 (the function of which will be hereinafter explained) are mounted in a tubular socket 4. To the feed-bar 2 is secured an india-rubber ink-reservoir 5. A metal strip

6 is disposed alongside the reservoir 5, said strip being of a springy nature and normally tending to occupy a position in which it is not pressing on (so as to collapse or flatten) the reservoir. The strip may be secured to the feed-bar 2 or to the reservoir itself. Formed on, or suitably secured to, the socket 4 is a button or lug 7 which is adapted to project outwardly from or through a longitudinal slot 9 in the barrel 8, the latter acting as a holder for the parts above referred to.

Pivottally mounted within the slot 9 is the self-filling lever 10 which cooperates with the strip 6 and reservoir 5 in the usual manner of such devices.

A non-removable cap or endpiece 11 fitted to the barrel 8 is formed with an aperture 11' through which the nib is projected for use by sliding the lug 7 along the slot 9. When the nib is in the inoperative position, it is housed and completely concealed within the cap or end piece 11, as shown in Figs. 1 and 2. In this position, the aperture 11' is closed by the part 12 of a resilient member 13 the other end of which is carried by a ring or collar 13' which is fitted tightly within the cap 11 as shown in Fig. 2. The cap is internally recessed or shouldered to form an abutment for the ring 13', but at the portion corresponding to the position of the strip 13 the cap is formed with a longitudinal groove 11''. It will be seen that the member 13 and the closure element 12 are also completely enclosed within the cap 11. Further, the construction and arrangement of this member (13) is such that it normally tends to assume or occupy the position shown in Fig. 2 wherein the part 12 is closing the aperture 11' when the nib is retracted within the housing 11.

If the lug 7 is caused to move outwardly along the slot 9, the nib 1 (and its associated parts 2, 3, 4, 5, and 6) move relatively to the barrel 8 so as to present the pen ready for use. The first part of this movement causes the socket 4, that is to say the forward end or edge thereof, to engage with the member 13. The consequential displacement of this member causes the part 12 to uncover the aperture 11' so as to permit the free passage therethrough of the nib 1 in the continued movement of the lug 7.

By properly shaping the wall surrounding the aperture 11' and the cooperating closure-element 12, the entrance of dirt etc. as

well as the possible evaporation of ink through the aperture is prevented or minimized.

Further, when the pen is in the inoperative position, the attachment 3 (which corresponds in form and assemblage to the top-feed-bar of a twin-feed pen) is caused to press on to the nib so as to close the opening therethrough and thus prevent the escape 10 of ink. The operative face of the part 3, that is to say the surface adjacent the nib, is suitably padded. This face is pressed into contact with the nib when the pen is being manipulated to bring the nib into the retracted position owing to the abutment of the inner wall of the housing 11 with the tapering outer face of the part 3. When the pen is manipulated to bring the nib into the operative position, the pressure of the part 20 3 on the nib is released by virtue of the inherent resiliency of the part 3.

A pocket-clip 16, secured to the barrel at the end thereof nearest the nib, is so shaped that the button 7 moves up and down within 25 it. The clip may carry the member on which the filling-lever 10 is mounted. As shown more clearly in Figure 5, the lever 10 is pivoted within a bifurcated strip 10' secured to the pocket-clip 16. An extension 10'' is 30 suitably curved to fit between the upper end of the barrel and the inner wall of the part 11 so as to be firmly clamped in the position shown in Figures 1 and 2 when the part 11 is assembled over the barrel.

35 In order to protect the button 7 and to prevent its accidental displacement, especially when the pen is being placed in or removed from the pocket, the barrel 8 is formed with raised portions 15 which project beyond, and thus prevent fouling of, the button.

The button 7 is formed at one side with a slot or notch 7' which, when the nib is in the retracted position, straddles the lever 10 so 45 as to lock the latter against operation.

It will be understood that the invention is not limited to the precise construction of parts above described and shown on the drawings. To those skilled in the art to 50 which my invention relates, it will be obvious that many modifications are possible within the scope of the appended claims; for example, it is not essential that the pen be of the self-filling type. The method of and 55 means for actuating the nib and its associated parts into and out of the operative position and the construction, disposition, and method of operation of the closure member for the end-aperture, and which consti-

tute important features of the present invention, could be applied to a fountain-pen irrespective of the manner in which the same is filled with ink.

It will be understood that where in the foregoing description or in the subsequent 65 claims, a non-removable cap or end-piece is referred to, it is intended that the cap is non-detachable as regards the functioning thereof in relation to the presentation of the nib for writing or its enclosing when not so 70 required. It will be appreciated by those in the art that in the construction hereinbefore described and shown on the drawing the end-piece or cap 11 is actually a separate part merely for the purpose of assemblage, 75 etc.

I claim:

1. A self-filling fountain-pen comprising a nib, a support therefor having an attached ink-reservoir, means carried by the nib-support for moving the latter so as to cause the nib to be projected through an aperture in the end of the pen or to be retracted within the latter, a self-filling lever, and means whereby the lever is locked against operation when the nib is in the retracted position.

2. A fountain-pen having an aperture in the end thereof through which the nib may be projected, and a resilient closure-member 90 which is completely enclosed within the end portion of the pen and automatically closes said aperture when the nib is withdrawn therethrough into a concealed position within the pen body.

3. A fountain-pen having a non-detachable cap or end-piece, a slidable nib-support, means whereby the nib may be projected out of an aperture in the end of the pen or withdrawn within the latter, a non-rotatable resilient closure-member for said aperture fitted within said end-piece, means associated with the nib and adapted to co-operate with the surrounding portion of the pen to shut off the flow of ink through the nib 100 when this is in the last-mentioned position.

4. A fountain-pen of the self-filling type having a nib adapted to be housed within the tubular wall of the pen or to be projected through an end aperture and a slid- 110 able nib-support, having a part which overlies the self-filling lever, when the nib is in the retracted or inoperative position.

PREM NARAYAN.
